LEVEL BLADE MOUNTING

Arnel T. Erickson, Hutchinson, Minn.

Application April 26, 1955, Serial No. 503,979

4 Claims. (Cl. 37—146)

This invention comprises novel and useful improvements in a level blade mounting, and more specifically relates to a heavy duty earth moving and earth leveling apparatus specifically adapted for heavy construction work, such as road construction, airport runways, super highways, dams and any other construction requiring filling and extensive earth moving and leveling operations and which necessitate uniform compaction of the filling material.

The principal object of this invention is to provide an apparatus adapted for heavy duty earth leveling and moving operations and which shall have an improved means for raising and lowering the earth working implement of the apparatus.

Yet another object of the invention is to provide an apparatus in conformity with the preceding object in which the control of the vertical adjustment of the earth working implement may be effected from a remote location.

Still another object of the invention is to provide an apparatus as set forth in the preceding objects wherein the power operating means of a tractor may be advantageously employed for controlling the vertical adjustment of the earth handling implement.

Yet another object of the invention is to provide an apparatus in conformity with the foregoing objects in which a compacting roller may be employed as the supporting structure of the apparatus and wherein the vertical adjustment of the earth working implement may be effected without interfering with the operation of the compacting roller.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of a preferred embodiment of apparatus in accordance with the principles of this invention, there being shown the rear portion of a conventional tractor to which the present apparatus is applied, a portion of a pivotal connection of the apparatus being shown in horizontal section therein;

Figure 2 is a side elevational view of the arrangement of Figure 1, the apparatus being shown with its earth working implement in its lowered and working position;

Figure 3 is a view similar to Figure 2 but showing the apparatus with its implement in raised position;

Figure 4 is a vertical transverse sectional view taken substantially upon the plane indicated by the section line 4—4 of Figure 3, parts being broken away;

Figure 5 is a detail view taken in vertical transverse section substantially upon the plane indicated by section line 5—5 of Figure 3 and showing in particular the pivotal connection of the front and rear frames of the ap-

2

paratus and the manner in which the spring is mounted thereon;

Figure 6 is a fragmentary perspective detail view showing one of the supports for the ends of the spring; and

Figure 7 is a perspective end detail view showing the rigging of the cable upon the pulleys of the vertical adjusting means for the implement.

Figure 8 is a plan view of a second embodiment of my invention with only a portion of the hydraulic lines and drawbar being shown, said view illustrating hydraulic means for flexing the forward and rear sections of the tow frame relative to one another;

Figure 9 is a fragmentary vertical side elevation of Figure 8, said view illustrating the sections of the tow frame flexed to elevate the blade mounted thereon.

In the accompanying drawings, a conventional form of tractor having an operator station thereon is indicated generally by reference numeral 10, said tractor having a drawbar 12 and an operator controlled actuator 14 which is also referred to as a power operated power take off winch or drum. The tractor 10 is a source of power for moving the tow-frame, said tow-frame including a tongue 16, and a pair of link portions 20, 22 otherwise referred to as front frame 20, and a rearwardly extending frame 22. The tongue 16 which is rigidly connected to the central portion of and forming a part of the front frame 20 is detachably secured to the draw bar 21 of the aforementioned tractor by pivot pin 18. Associated with the front frame is a rearwardly extending frame 22 upon which is journaled a conventional compacting roller 24 which is employed both to compact the earth moved and leveled by the apparatus and also to support the rear portion of the apparatus. Thus a hitch is provided at the distal end of the forward frame to be connected to a towing vehicle while the distal end of the rear frame is constructed to be mounted above a roller.

The front and rear frames 20 and 22 are longitudinally aligned, and each includes a pair of longitudinal side members 25 for the front frame and 26 for the rear frame. As shown more clearly in Figure 5, the rearward extremities of the front frame members 25 are bifurcated and receive therebetween the forward extremity of the rear frame longitudinal members 26. A pair of pivot pins 28 hingedly connect these extremities for vertical pivoting movement of the frames at their proximal or mutually adjacent ends.

The pivotal connection of the front and rear frames, upon at least one side thereof, is provided with a saddle 30, see Figure 5, which supports at its midportion a leaf spring assembly 32. The saddle is operatively connected to the pivot pin, as for example, by being connected directly to the bifurcated extremity of one of the members 25, or one of the members 26, or to the pivot pin thereof.

Each of the side frame members 25 and 26 is provided with a laterally extending pin 34, as shown in Figure 6, which pins are adapted to receive and support the opposite extremities of the leaf spring assembly 32. The arrangement is such that the spring normally urges the pivotal connection of the front and rear frames upwardly, into the position shown in Figure 3, thereby lifting the implement carried by the frames from the soil, until such time as the frames at their hinged connection are forced downwardly to thereby lower the implement, as shown in Figure 2.

The implement above referred to may be of any type, for leveling, scarifying or otherwise working the soil, and as illustrated, consists of an earth cutting and moving blade 36, mounted upon suitable brackets 38 and depending from one of the frames adjacent the pivotal connection of the same. As shown in Figure 2, the blade is mounted upon the front end of the rear frame, although

in some instances, it may be carried by the rear end of the front frame, if desired.

In order to force the pivotal connections of the front and rear frames downwardly against the opposition of the leaf spring, a vertical adjusting means is provided. This consists of a pair of upstanding brackets 40 and 42 which are rigidly connected to and extend upwardly from the central portions of the front and rear frames adjacent their mutually adjacent ends. Sets of pulleys 44 and 46 are carried by the upper ends of these brackets, and a cable 48 is entrained over these pulleys and over an idler pulley 50 which is mounted upon a swivel support 52 upon the front frame member. Although any desired number of such pulleys may be provided, depending upon the mechanical advantage which it is desired to apply to the vertical adjustment of the pivotal connection of the frames, two pulleys carried by each bracket are deemed to be generally sufficient. The aforementioned spring, upstanding brackets 40, 42, pulleys 44, 46 and the portion of the cable 48 interconnecting the pulleys along with the associated parts connected thereto and mounted on the tow-frame for causing the link portions of said tow-frame to pivot about the pivotal axis are also known as an actuating linkage. The portion of the cable 48 extending forwardly of the forward frame and being connected to the operator controlled actuator would in this event be the control element for the actuating linkage mounted in the tow frame.

As shown in the diagrammatic view of Figure 7, the cable has one end secured to one of the pulleys 46, is then wound over a pulley 44, then over the other pulley 46, then over the other pulley 44, is entrained over the guide pulley 50 and has its other end secured to the previously mentioned winch or drum 14. As will now be apparent, when the winch is operated, the cable will be tightened, thus drawing the brackets or arms 40 and 42 together at their upper ends, thereby vertically depressing the pivot pins against the resistance of the spring 32 and lowering the implement 36 from its raised position of Figure 3 to its lowered position of Figure 2. It is thus obvious that the power operating means of the tractor may be employed to vertically adjust the blade or other implement carried by the device, and this adjustment is effected without interfering with the operation of the compacting roller 24.

It is within the scope of this invention to use various other means for operating the blade leveler. For example, in place of using the cables 48 and the various elements associated therewith to flex the sections of the tow frame, the hydraulic actuator means of the second embodiment of my invention (see Figures 8 and 9) may be utilized.

In providing hydraulic actuator means for operating the blade leveler, a hydraulic power take off 60 (schematically illustrated) which includes the operator controlled actuator is provided in place of means 14 of the first embodiment. A pair of hydraulic fluid lines 61, 62 are fluidly connected to the hydraulic take off 60 and extended in a rearward direction to respectively be connected at the opposite ends of the "two-way" cylinder 64 which is mounted on the tow frame. The cylinder 64 has a T shaped bracket 65 secured to one end thereof, said bracket in turn being pivotally secured to the upper end of the front upstanding bracket 40 by a pivot member 69. The cylinder has a piston (not shown) mounted therein, said piston being connected to a piston rod 67.

A transverse sleeve 66 is secured to the end of the piston rod and is pivotally secured to the upper end of the bracket 42 by a pivot member 69. Except for the modification of the operator controlled actuator 14 and elimination of the cable 48, bracket 52, pulleys 50, 44, and 46 and the substitution therefor or the replacements thereof with the above described actuator means, the structure of the second embodiment of the blade leveler of my in-

vention is substantially the same as the structure of the first embodiment thereof.

The operation of the second embodiment is generally the same as that of the first embodiment except for different means being provided for flexing the sections of the tow-frame. As may be noted, a fluid line 61 extends from the power take-off 60 to be connected to the forward end of the cylinder 64 while the fluid line 62 extends from said power take-off to be connected to the rearward end of the same cylinder. Thus means is provided whereby the piston rod may be moved to an extended position (Figure 9) when fluid is forced through the line 61 into the cylinder and thereby elevate blade 36 and to a retracted position when fluid is forced through line 62 into the rearward end of the same cylinder and thereby lower blade 36.

It is to be understood that only a single fluid line (not shown) need be provided since with appropriate type of power take-off connections, the leaf spring 32 will flex 20 the forward and rear frames in an upward direction and thus cause the piston rods 67 to move to an extended position. Then to lower the earth working blade, fluid would be forced through the aforementioned single line to retract the piston rod and move the upstanding brackets 25 42, 44 toward one another. Further, other implements, such as scarifiers, disks and the like may be substituted for the blade 36, in accordance with the particular functions to be performed.

The foregoing is considered as illustrative only of the 30 principles of the invention. Further, since numerous modifications and changes will readily occur to those skilled in the art, it is not desired to limit the invention to the exact construction and operation shown and described, and accordingly, all suitable modifications and 35 equivalents may be resorted to, falling within the scope of the invention as claimed.

What is claimed as new is as follows:

1. An earth working and compacting device constructed to be pulled by the traction vehicle having thereon an operator station and an operator controlled actuator, said device comprising a heavy earth roller having an axis of rotation, a longitudinally extending tow frame composed of a forward frame and a rear frame, means hingedly connecting the mutual adjacent ends of said forward frame and said rear frame for pivotal movement relative 40 to one another, said hinge means having a pivot axis that is generally transverse to the length of said tow frame, said rear frame connected to the roller at said roller axis, said forward frame having a distal end shaped to form a hitch, an earth working implement mounted on said tow frame adjacent said hinge means and in depending relation to the tow frame, an actuating linkage means operatively connected to the rear frame between the connection of the roller to said frame and the pivotal axis of the front and rear frames and also operatively 45 connected to the front frame between said hitch and the pivotal axis of the front and rear frames for flexing said front and rear frame relative to one another to selectively lower and raise said earth working implement, said 50 actuator means including a bracket which forms the operative connection to the front frame, a second bracket that forms the operative connection to the rear frame, and means connecting said brackets for moving the brackets towards one another.

2. The apparatus of claim 1 further characterized in that the means connecting said bracket includes a hydraulic cylinder and piston mounted to extend between said brackets.

3. The apparatus of claim 1 further characterized in that the actuator linkage means includes a spring that is connected at one end to the rear frame intermediate the pivot axis and the roller axis and at the other end to the forward frame intermediate the hitch and the pivot axis.

4. An earth leveling apparatus comprising a pair of

longitudinally aligned frames, pivot means hingedly connecting the mutually adjacent ends of said frames for vertical pivoting movement, an earth working blade mounted upon one of said frames in depending relation and closely adjacent said pivot, a spring operatively connected with said pivot means and said frames for urging the pivoted ends of the frames and said blade upwardly, a pair of brackets rigidly secured to and rising from mutually adjacent ends of said frames, said brackets being upwardly divergent, means connected to the upper ends of said brackets for moving the same towards each other to thereby depress the hinged ends of the frame against the resistance of the spring, said spring comprising a leaf spring assembly having its midportion connected to said pivot means and having its ends each connected to one of said frames.
